UNITED STATES PATENT OFFICE

169,463

LIGHTING FIXTURE OR THE LIKE

Andrew Vollrath, Whiting, Ind.

Application January 2, 1952, Serial No. 17,881

Term of patent 3½ years

(CL. D48—23)

To all whom it may concern:

Be it known that I, Andrew Vollrath, a citizen of the United States, residing at Whiting, in the county of Lake and State of Indiana, have invented a new, original, and ornamental Design for a Lighting Fixture or the like, of which the following is a specification, reference being had to the accompanying drawing, forming a part thereof, in which:

Fig. 1 is a front view of a lighting fixture, showing my new design;

Fig. 2 is a right elevational view thereof, the view from the left being symmetrical therewith; and

Fig. 3 is a bottom plan view thereof.

I claim:

The ornamental design for a lighting fixture or the like, substantially as shown and described.

ANDREW VOLLRATH.
